GEORGE M. CÔTÉ, OF PITTSBURGH, PENNSYLVANIA, ASSIGNOR OF ONE-THIRD TO
J. HARVEY HARRISON, OF PITTSBURGH, PENNSYLVANIA.

RAIL-FASTENING DEVICE.

1,111,528.

Specification of Letters Patent.

Patented Sept. 22, 1914.

Pittsburgh, Pennsylvania. Application filed January 15, 1914. Serial No. 812,195.

To all whom it may concern:

Be it known that I, GEORGE M. CÔTÉ, a citizen of the United States, and residing in the city of Pittsburgh, in the county of Allegheny and State of Pennsylvania, have invented or discovered new and useful Improvements in Rail-Fastening Devices, of which the following is a specification.

My invention consists in new and useful improvements in means for fastening or securing railway-rails to metal cross-ties of the girder or I-beam type.

The fastening means now adopted involves the use of bolts and nuts or other devices provided with threaded engagements. Such devices are expensive and require constant care and inspection, since the jar and vibration of traffic loosen the same. The insulation of the rail from the ties, as required in electrical signaling, involves great difficulty and expense, and adequate provision for shifting or varying the position of the rail, to compensate for wear upon the rail head and to provide for the varying gage on curves, is not possible.

My invention conveniently, effectively and inexpensively accomplishes all of the purposes and overcomes all of the difficulties above mentioned.

The invention includes a clamp member having an arc-shaped body coacting with apertures in the top flange of the tie and an arc-shaped seat cut in the vertical web of the tie. One end, the head, of the clamp is provided with one or more faces which are adapted to engage the rail base, while the other end, or tail, of the clamp extends above the top of the tie and is slotted for the reception of a wedge-key which engages the tie top and clamps the head down onto the rail base. The plurality of engaging faces of the head permits the rail to be shifted or its position varied in relation to the tie. Convenient and inexpensive means are provided for insulating the rail from the tie and from the clamp. It will be understood that a pair of clamps are used to secure a rail to a tie, one engaging either side of the rail base.

In the accompanying drawings, which are merely illustrative of the principles of my invention and not intended to limit the scope thereof to the construction shown, Figure 1 is a broken side elevation of a cross-tie having a rail, shown in section, sec-

cured thereto by my present invention; Fig. 2 is a broken enlarged longitudinal section of the tie showing one of the clamps mounted therein; Fig. 3 is a broken bottom plan view of the tie; Fig. 4 is a sectional view looking to the right from the dotted line IV—IV in Fig. 2, and Figs. 5 and 6 are perspectives of the insulating members.

The following is a detailed description of the drawings. A is an I-beam or girder cross-tie of metal having a bottom flange 1, a vertical web 2 and a top flange 3. B is a railway rail mounted upon said tie A and supported by a portion of the top flange 3 which I term the rail-platform and mark 4. At either side of said rail platform an aperture 5 is punched through the flange 3, said holes being elongated toward each other so that the distance between them is somewhat less than the width of the base of the rail. In the rear of each aperture 5 is punched a second aperture 6. The two apertures 5 and 6 are connected by means of an arc-shaped seat 7 cut through the web 2 of the tie. The upper and lower walls of said seat are concentric, and the forward or inner end of said seat is recessed below the elongation of the aperture 5 as at 8. Thus an arc-shaped bearing or projection 9 is formed which depends from the top flange 3 of the tie.

C is a clamp member having an arc-shaped body adapted to be slid into the seat 7 through the apertures 5 and to be mounted in said seat. The head of said clamp is enlarged and provided with one or more faces, such as a, b and c which are adapted to be clamped down against the base of the rail B. These engaging faces are associated in the form of steps, as shown, separated by angular portions. The other end or tail of the clamp extends up through the aperture 6 and is slotted, as at 10 to receive the wedge key D which bears against the top of the tie and clamps the head of the fastener down against the rail base. I prefer to use a split key, as shown so that it may be locked stationary when the desired tension against the rail base has been effected. The head of the clamp is laterally enlarged, as at 11, to prevent its slipping down through the aperture 5.

The lateral position of the rail in relation to the rail-platform 4 determines which

gaging face of a clamp engages the rail base. Thus in Fig. 1 the rail is shown shifted to its position to the right, the lowest face, *c*, of the right hand clamp engaging 5 the rail base, while the top face *a* of the left hand clamp engages said base. When the rail is positioned centrally of the rail base, the faces *b* of both clamps engage the rail base. When the rail is shifted to its position 10 to the left, the lowest face of the left hand clamp and the top face of the right hand clamp engage the rail base. Owing to the wedge character of the key *D*, the head may be as firmly forced against the rail base 15 whatever position the clamp may be caused to assume.

The correspondence between the contour of the clamp and its seat 7 maintains a perfect bearing at all times for the body of the 20 clamp and the strain and tension are readily and completely assumed by the body of the tie without undue strain upon the clamp or the walls of the seat 7. The projection forms the fulcrum. The curved form of 25 the seat and the clamp body enables the clamp to be tightened snugly against the rail base without difficulty.

To insulate the rail, so that it may be used 30 as part of a signal circuit, I provide a mat 12, of hard insulating material, such as fiber, which is interposed between the rail platform 4 and the rail base, as shown. Such mat is provided with integral ears 13 which fit on either side of the heads of the 35 clamps *C* and thus hold the mat against displacement. To insulate the rail from the fasteners, an L-shaped insulating member 14, of similar material to that of mat 12, is used. The laterally extended head 15 of 40 said member 14 is interposed between the rail base and the face of the head which is to be clamped against the former, while the depending legs, 16, of the member 14 extend downwardly through the elongated 45 portion of the aperture 5 into the recessed portion 8 of the seat 7. To prevent possible contact between the web 2 of the tie and the lower end of the member 14, the depending legs 16 of the latter are preferably bifurcated 50 as shown to straddle said web.

It is evident from the foregoing that my 55 invention provides inexpensive, yet durable and effective means for securing a rail to a cross-tie, which will permit of ready gage adjustment and perfect insulation of the rail. The contact between the clamps and the rail is always positive and will not loosen unless the wedge key is intentionally contracted by means of a suitable tool and 60 the wedge driven back in the slot 10. The clamp, however, is readily and easily installed, removed or adjusted to allow change in gage.

What I desire to claim is:—

1. In railway devices for the purpose de- 65 scribed, the combination of an I-beam cross-tie provided with a pair of alined apertures in the top flange thereof and an arc-shaped seat cut in the web thereof and connecting said apertures; a clamp member having an 70 arc-shaped body adapted to be mounted in said seat, the head of said clamp protruding through one of said apertures to engage the rail while the tail of said clamp protrudes through the other aperture, and a second 75 member bearing against the top of said tie and exerting an upward tension on said tail.

2. In railway devices for the purpose de- 80 scribed, the combination of an I-beam cross-tie provided with a pair of alined apertures 85 in the top flange thereof and an arc-shaped seat cut in the web thereof and connecting said apertures, a clamp member having an arc-shaped body adapted to be slidably mounted in said seat, the head of said clamp 90 protruding through one of said apertures to engage the rail, a plurality of rail engaging surfaces being provided on said head, while the tail of said clamp protrudes through the other aperture, and a second 95 member bearing against the top of said tie and exerting an upward tension on said tail.

3. In railway devices for the purpose de- 95 scribed, the combination of an I-beam cross-tie provided with a pair of alined apertures 100 in the top flange thereof and an arc-shaped seat cut in the web thereof and connecting said apertures, a clamp member having an arc-shaped body adapted to be mounted in said seat, the head of said clamp protruding through one of said apertures to engage the rail, while the tail of said clamp is slotted and protrudes through the second aperture, and a wedge member adapted to engage said slot and bear upon the top of said tie. 105

4. In railway devices for the purpose de- 110 scribed, the combination of an I-beam cross-tie provided with a pair of alined apertures in the top flange thereof and an arc-shaped seat cut in the web thereof and connecting 115 said apertures, a clamp member having an arc-shaped body adapted to be slidably mounted in said seat, the head of said clamp protruding through one of said apertures to engage the rail, said head being provided with a plurality of rail engaging faces, while the tail of said clamp is slotted and protrudes through the other aperture, and a wedge member engaging said slot and bearing upon the top of the tie. 120

Signed at Pittsburgh, Penna., this 14th day of January 1914.
